UNITED STATES PATENT OFFICE.

EZECHIEL WEINTRAUB, OF NEW YORK, N. Y.

MICROPHONE.

Application filed May 1, 1919. Serial No. 294,062.

To all whom it may concern:

Be it known that I, EZECHIEL WEINTRAUB, a citizen of the United States, residing at New York, in the county of New York, State 5 of New York, have invented certain new and useful Improvements in Microphones; and I do hereby declare the following to be a full, clear, and exact description of the invention, such as will enable others skilled 10 in the art to which it appertains to make and use the same.

The present invention relates to improvements in microphones for the electrical transmission of speech or periodic sounds 15 having a frequency within the range of good audibility, but more particularly to microphones of selective sensitiveness which respond to sounds of a frequency within the range of human speech and which respond 20 extremely feebly, or, not at all, to sounds of a very low frequency or aperiodic disturbances such as noises or mechanical shocks.

In the usual type of commercial microphone, carbon granules are loosely confined 25 between two carbon electrodes, of which one is stationary and the other made to vibrate by the impinging sound waves. Thus, when the microphone is connected in an electric circuit, the contact resistance of the granules 30 varies in unison with the varying pressure of the vibrating electrode. Physical and electrical properties of the carbon granules permit microphones of this type to respond 35 equally as well to low frequency periodic sounds or aperiodic disturbances as to sounds of the frequency desired to be transmitted.

In the preferred form of my selectively sensitive microphone two carbon electrodes 40 are provided between which are loosely confined carbon coated electrically conductive particles, having a higher specific gravity than carbon, and its action involves, as in the case of the carbon granule microphone, 45 the variation of contact resistance of the particles in unison with the varying pressure of the vibrating electrode.

The selective sensitiveness of my improved microphone is based on the fact discovered 50 by me, that electrically conductive particles having a higher specific gravity than carbon, although they respond feebly as compared to the carbon granule type of microphone, respond more feebly to undesirable 55 aperiodic frequencies or low frequency sounds than to sounds within the range of

frequency of human speech. I have also discovered that the higher the specific gravity of the particles, the more marked is the non-response to undesirable aperiodic disturbances or low frequency sounds, while the response to frequencies within the range of human speech does not vary in the same proportion with increase in specific gravity.

I have pointed out above that my selectively sensitive microphone responds more feebly to periodic sounds having a frequency within the range of human speech than carbon granule microphones, and in order to increase the value of the current variations 60 produced by the varying resistance of the microphone, it will usually be advantageous 65 to include in apparatus utilizing my improved microphone, means for amplifying the current variations. The most convenient and efficient means available for this purpose is a three-electrode vacuum tube 70 amplifier, by means of which the current variations produced by the microphone may be amplified to any desired value. In this 75 manner, the response of my selectively sensitive microphone may be made equal to, or greater than, the response of a carbon granule microphone to any given sound within the range of frequency of human 80 speech and at the same time reduce to a negligible value the effect of undesirable 85 aperiodic and low frequency periodic sounds.

In the accompanying drawings:

Fig. 1 illustrates my invention applied to 90 a well-known type of microphone;

Fig. 2 is an enlarged sectional view showing the arrangement of the particles between the two electrodes;

Figure 2^a is an enlarged cross section of 95 a carbon coated granule or ball as shown in Figure 2.

Fig. 3 illustrates a method for amplifying the current variations produced by my improved microphone.

Referring now particularly to Fig. 1, which shows a carbon electrode 1, having hemispherical cavities 2 in its surface adapted to retain carbon-coated metallic balls 3, in contact with a carbon electrode 4, adapted 100 to be set into vibration by the impinging sound waves.

Referring now to Figures 2 and 2^a the arrangement of the carbon coated electrically conductive particles 3, is clearly shown 110 with reference to the electrode 1, containing a cavity 2 retaining the particles 3 so that

they are confined between the electrode 1 and the vibrating electrode 4. Figure 2^a shows a single carbon coated particle 3 which comprises an electrically conductive body 10, preferably of a higher specific gravity than carbon and a carbon coating 11 deposited or placed on the surface thereof.

Referring now to Fig. 3, it will be observed that variations of current in the electric circuit including the electrodes 1 and 4 of my improved microphone, will be amplified by the three-electrode vacuum tube amplifier 5, and indicated by the receiving device 6. It should be noted here that the function of the vacuum tube amplifier is solely to increase the value of the pulsating current produced by the variation of the resistance of the microphone, while at the same time producing no distortions of this current. An amplifier of this type, it is well known, will amplify all current variations produced by a microphone due to the combined effect of aperiodic disturbances and periodic vibrations within the range of human speech. For this reason, an amplifier used in connection with a non-selectively sensitive microphone, such as a carbon granule microphone, produces no material advantage over a carbon granule microphone operating without amplification because the aperiodic vibrations or other undesirable disturbances will be amplified to the same degree as the desired periodic vibrations within the frequency of human speech.

For obvious reasons, the selective sensitivity of my improved microphone recommends its use in connection with apparatus located in many environments which would be unfavorable to the use of carbon granule microphones. For example, in connection with wireless telephone apparatus installed on an aeroplane where the elimination of motor and propeller noises is important, and in submarine signalling where the elimination of water noises is important. The use of my improved microphone is especially advantageous in connection with apparatus for people hard of hearing and will eliminate the constant buzzing and loud response to aperiodic vibrations or other undesirable disturbances which is an inherent defect in carbon granule microphone apparatus. In long distance telephony, the use of my improved microphone will aid considerably in improving the quality of transmitted tones because of the elimination of noises, etc.

I have obtained the best results with my improved microphone when metallic balls of high specific gravity were used as the varying resistance, particularly balls formed of metals having specific gravities between that of copper and that of platinum. However, good results have been obtained with metallic balls having a specific gravity less than copper but greater than carbon.

In order to obtain the advantages peculiar to contact resistance between carbon surfaces in microphones and to avoid possible oxidation when using certain metals, and to avoid other chemical action, the balls are preferably coated with a thin layer of carbon or graphite. This coating may be accomplished in any well known manner. For example, by heating the balls in an iron tube to a red heat and passing hydro-carbon vapors through the tube which will decompose and deposit carbon on the balls. If the tube is rotated simultaneously with the deposition of the carbon, an even coating of carbon will be obtained on the surface of the balls. Other methods of coating the balls with carbon such as the slow carbonization of viscous organic material mixed with carbon or graphite applied to the surface of the balls and the simple method of rolling lead balls in fine graphite dust, have yielded good results.

While I have illustrated my invention as applied to a particular type of microphone, it should be understood that my invention may be utilized in any type of microphone which depends for its action on a varying resistance loose contact, that modifications may be made in the shape or type of particles having a specific gravity greater than carbon and other methods of amplification may be utilized other than that shown in the drawing without departing from the spirit and scope of my invention.

I claim:

1. A selectively sensitive microphone adapted to translate sounds of periodic high frequency into corresponding electric pulsatory currents, but to respond very feebly to sounds produced by aperiodic or low frequency periodic vibrations comprising, two electrodes adapted to be connected in an electric circuit and carbon coated particles having a higher specific gravity than carbon confined between said electrodes, one of said electrodes adapted to be vibrated by sounds impressed thereon. 100

2. A selectively sensitive microphone adapted to translate sounds of periodic high frequency into corresponding electric pulsatory currents, but to respond very feebly to sounds produced by aperiodic or low frequency periodic vibrations comprising, two electrodes adapted to be connected in an electric circuit and carbon coated metallic particles having a higher specific gravity than carbon confined between said electrodes, one of said electrodes adapted to be vibrated by sounds impressed thereon. 105

3. A selectively sensitive microphone adapted to translate sounds of periodic high frequency into corresponding electric pulsatory currents, but to respond very feebly to sounds produced by aperiodic or low frequency periodic vibrations comprising, two 110

electrodes adapted to be connected in an electric circuit and carbon coated metallic balls having a higher specific gravity than carbon confined between said electrodes, one of 5 said electrodes adapted to be vibrated by sounds impressed thereon.

4. In electrical apparatus for selectively translating sounds into corresponding pulsatory electric currents, the combination of 10 a circuit containing a selectively sensitive microphone adapted to translate sounds of periodic high frequency into corresponding feeble electric pulsatory currents, said microphone adapted to respond feebly to 15 sounds produced by aperiodic or low frequency periodic vibrations and comprising two electrodes adapted to be connected in said circuit and having carbon coated particles of a higher specific gravity than carbon confined between said electrodes, and electric current amplifying means associated with said circuit adapted to amplify the feeble electric pulsatory currents produced in the circuit.
- 20 5. In electrical apparatus for selectively translating sounds into corresponding pulsatory electric currents, the combination of a circuit containing a selectively sensitive microphone adapted to translate sounds of periodic high frequency into corresponding feeble electric pulsatory currents comprising 25 two electrodes adapted to be connected in said circuit having carbon coated metallic particles of higher specific gravity than carbon confined therebetween, and a thermionic vacuum tube amplifier associated with said circuit adapted to amplify the feeble electric pulsatory currents produced in the circuit.
- 25 6. In electrical apparatus for selectively translating sounds into corresponding pulsatory electric currents, the combination of a circuit containing a selectively sensitive microphone adapted to translate sounds of periodic high frequency into corresponding feeble electric pulsatory currents but to respond very feebly to sounds produced by aperiodic or low frequency periodic vibrations and comprising two electrodes adapted

to be connected in said circuit having carbon coated metallic balls of a higher specific gravity than carbon confined between said electrodes, and electric current amplifying means associated with said circuit adapted to amplify the feeble electric pulsatory currents produced in the circuit. 35

6. In electrical apparatus for selectively translating sounds into corresponding pulsatory electric currents, the combination of a circuit containing a selectively sensitive microphone adapted to translate sounds of periodic high frequency into corresponding feeble electric pulsatory currents comprising 40 two electrodes adapted to be connected in said circuit having carbon coated metallic particles of higher specific gravity than carbon confined therebetween, and a thermionic vacuum tube amplifier associated with said circuit adapted to amplify the feeble electric pulsatory currents produced 45 in the circuit.

7. The combination, in a telephonic audiophone, comprising a one-way transmission circuit including sound collecting and reproducing devices, of audio-frequency 50 transforming means, and vacuum tube relay means whose input circuit is connected through said transforming means with said collecting device, and whose output circuit is connected with said reproducing device. 55

In testimony whereof I affix my signature.

EZECHIEL WEINTRAUB.
